FLYWHEEL SYSTEM

Stanley D. Livingston, Freeport, N. Y., assignor
to R. Hoe & Co., Inc., New York, N. Y., a corporation of New York

Application May 22, 1951, Serial No. 227,641

2 Claims. (Cl. 74—572)

1

This invention relates to improvements in fly wheel systems.

More particularly, the invention is concerned with the elimination of shock on drive gearing due to reversal of movement of a reciprocating mass. A typical application for the fly wheel system of the invention is in a packer box delivery, in which the reciprocation of the usual pusher arms, which have considerable inertia, imposes relatively severe loads on the gearing tending to limit the usefulness of such deliveries at high speeds, due to possible failure of the gearing.

It is an object of the present invention to permit increase in the speed of operation of such a reciprocating drive by stabilizing the load on the drive gearing, eliminating shock due to reversal of movement of the driven mass.

A further object of the invention is to provide fly wheel stabilized drive and reciprocating mechanism, in which the kinetic energy of the system as a whole may be maintained substantially constant, thus eliminating torque variation in the drive shaft supplying the power thereto, in so far as the torque variation is due to the inertia of the parts.

With the foregoing objects and still other objects which will appear in mind, the invention consists in the combination and arrangements of parts and details of construction which will now first be fully described with reference to the accompanying drawing and then be more particularly pointed out in the appended claims.

In the drawing:

Figure 1 is a plan view of a mechanism embodying the invention in a preferred form;

Figure 2 is a side elevation view of the mechanism of Figure 1;

Figure 3 is a section on the line 3—3 of Figure 2;

Figure 4 is a rear elevation of the fly wheel of Figures 2 and 3;

Figures 5 to 8 are diagrammatic views showing the position of certain parts in different angular positions of the fly wheel.

In Figure 2, the level of the table 1, with which the pusher arms 2 cooperate, is indicated in phantom. The invention is not concerned with the packer box apart from the pusher and drive therefor, and the packer box table and other parts may be of any desired construction. The arms 2 are fixed to a cross bar 3 and are pivotally mounted on a shaft 11 by means of an extension 4 of the middle arm 2. A link 5 is pivotally connected at 6 and 7 to a frame ele-

2

ment and to the extension 4. Shaft 11 is rotatably mounted in arms 9 which are pivotally supported from brackets 8 on pins 10. Wristpin 12 connects an arm 9 to pitman 13 and drive crank 14.

The crankshaft is carried in an anti-friction bearing 15 (Figure 3) and connected by an offset bracket 16 to fly wheel 17 which is driven by a shaft 18 supported in anti-friction bearings 19 and which is coaxial with the crankshaft.

Sector shaped weights 20, 21 and 22 are fixed to shafts 23 journaled in the fly wheel 17 and are driven by planet gears 24 meshing with idler gears 25 which, in turn, mesh with a stationary sun gear 26. The gear ratio between sun gear 26 and the planet gears 24 is two-to-one. Assuming counterclockwise rotation of fly wheel 17 in Figure 2, the planets 24 will rotate with respect to the fly wheel 17 at twice its angular velocity and in the opposite or clockwise direction. Since the movement of revolution of the pinions will be in the same direction as the fly wheel and at equal angular velocity, the net rotation of the planets 24 with respect to the stationary frame structure will be at the same angular velocity as the fly wheel but in the opposite, or clockwise, direction.

Figures 5 to 8 show schematically the position of the parts as the fly wheel 17 is rotated in 90 degree steps from the position of Figure 2, the center of gravity C of each weight travelling in the flat elliptical path P. In the position of Figure 5, which corresponds to that of Figure 4, the torque exerted against the fly wheel in starting the return movement of the pusher mechanism is clockwise, but the weight 21 being in its outer position exerts counterbalancing counterclockwise torque, so that by a suitable relation of the dimensions and masses of the parts, the shock due to starting the reciprocating pusher mass from the position of rest is substantially eliminated. As the parts move from the position of Figure 5 to that of Figure 6, the clockwise torque against the fly wheel due to the pusher decreases and the counterclockwise counterbalancing torque of the weight 21 correspondingly decreases until, as shown in Figure 6, this counterbalancing torque is reduced substantially to zero. The movement of the parts from the position of Figure 6 to that of Figure 7 involves a slowing down of the reciprocating pusher mass by the fly wheel so that the torque exerted thereby on the fly wheel is counterclockwise. The weight 21 having passed under the axis of rotation of the fly wheel will now

exert an increasing clockwise torque, thus continuing to balance the pusher in its reciprocation. As the fly wheel continues to rotate, there is thus at all times a counterbalancing of the torque on the fly wheel due to the reciprocating mass, by the torque due to the weight 21. For a theoretically perfect counterbalance, the distance between the center of gravity of weight 21 and the axis of rotation of the fly wheel 17 should be equal to the distance between the axis of shaft 23 and shaft 18. In this case, the center of gravity of the weight 21 will move back and forth in a straight line through the axis of shaft 18 and fly wheel 17. Movement of the center of gravity C in the flat elliptical path P, however, furnishes sufficient counterbalancing to eliminate undue strain on the gears and permits a more compact construction.

The weights 20 and 22 serve to balance the variation in kinetic energy of the system due to the movement of the center of gravity of the weight 21 toward and away from the axis of the fly wheel, with consequent change in moment of inertia of the fly wheel and weight 21 considered as a unit. Thus, it will be noted that in the position of Figures 5 and 7, when the weight 21 is in an outer position, weights 20 and 22 are in an inner position, while in the position of Figures 6 and 8, when the weight 21 is in an inner position, weights 20 and 22 are in an outer position. By proper selection of the masses and dimensions, it thus becomes possible to eliminate or to smooth out to any required degree the variation in moment of inertia of the

fly wheel caused by movement of the weight 21. As a practical matter and apart from such minor disturbing factors as crank errors, shock on the gear teeth in the drive is thereby eliminated.

5. What is claimed is:

1. A fly wheel system for reciprocating drives comprising a fly wheel, a counterbalance weight rotatably mounted thereon for movement toward and away from the fly wheel axis, a pair of weights similarly and symmetrically mounted with respect to the fly wheel axis, gearing for rotating the counterbalance weight oppositely and at the same angular velocity as the fly wheel, whereby the said counterbalance weight may balance torque on the fly wheel due to a reciprocating mass driven thereby, and gearing for similarly rotating the said pair of weights, the said gearing being arranged to move the said pair of weights toward the fly wheel axis as the counterbalance weight moves away from the fly wheel axis, whereby the said pair of weights counteract variation in moment of inertia in the fly wheel system due to the movement of the counterbalance weight and the reciprocating mass.

2. A fly wheel system according to claim 1, in which the gearing for rotating the said weights comprises a stationary sun gear, planet pinions driving the weights and intermediate idler gears between the sun gear and pinions, the drive ratio being two-to-one.
